UNITED STATES PATENT OFFICE.

FRANK A. PORTMAN, OF CHICAGO, ILLINOIS.

MERCHANTISE-DISPLAY BOX.

Application filed July 5, 1924. Serial No. 724,202.

My invention relates to certain novel and useful improvements in merchandise display boxes, and has for its principal object the provision of an improved construction of this character which will be highly efficient in use and economical in manufacture.

Another object of my invention is the provision of a display box of the character specified, especially designed to hold candy and 10 confections, and constructed with a merchandise holding extension or top adapted readily to be elevated into display position without disturbing the contents of the main box and without interfering with the removal 15 of the contents thereof when said extension is elevated into display position.

Another object of my invention is the provision of a display box of the character specified, in which the main part of the box and 20 the display or top extension may, for convenience and economy of manufacture and assembling, be made as integral parts, produced from a single blank of material.

Other objects will appear hereinafter.

25 The invention consists in the combinations and arrangements of parts hereinafter described and claimed.

The invention will be best understood by reference to the accompanying drawings 30 forming a part of this specification, and in which,

Fig. 1 is a view in perspective of my improved display box, the display extension or top being indicated in elevated or display 35 position by broken lines.

Fig. 2 is a central longitudinal section taken on the line 2—2 of Fig. 1.

Fig. 3 is a cross section on the line of 3—3 of Fig. 2.

Fig. 4 is a plan view of the blank for forming a merchandise display device.

In carrying out my improvements, I provide a main merchandise holding receptacle, preferably made in the form of a box body, 45 having a bottom 5, opposed side walls 6 and 7, opposed end walls 8 and 9, all formed from a single piece of material. The side wall 6 is made with integral end portions 6' and 6'', which, when the box is folded, are 50 first bent upwardly and then inwardly to lie flat against the inner surfaces of the respective ends 8 and 9 with which they are made fast by gluing or other suitable means. The side 7 is also made with end portions 7' and 55 7'', which, in a similar manner, are foldable

to lie flat on the inner surfaces of the respective ends 8 and 9.

According to an important feature of my invention, one of the walls of the box body, herein shown, by way of example, as the end wall 9, is made with an integral display extension 10, adapted on the dividing or corner line 11 to have movement relative to the box body, and having such dimensions as will enable it to fit snugly within the interior of the box body at the top end thereof as clearly illustrated in the drawing. This integral display extension 10 is provided with a window 12 for the display of merchandise in a manner presently to be described.

With the integral display extension 10 are formed integral opposed sides or sheets 13 and 14 having reinforcing portions 13' and 14', respectively, and further having ledge portions 15 and 16, respectively. As clearly shown in Figs. 2 and 3, the side portions 13' and 14' are each bent inwardly to lie flat upon their respective sides or sheets 13 and 14, while the ledge portions 15 and 16 are bent inwardly at right angles with respect to the respective portions 13' and 14', so as to extend in parallel relation to the display extension 10. The sides or sheets 13 and 14, contacting with the box walls 6 and 7, respectively, and reinforced thereby are of such length that when bent at right angles to the display extension 10, they will engage the bottom 5 of the main box, for the support of the display top 10 in horizontal position 90 substantially flush with the top edges of the sides and ends of the box, as clearly illustrated in the drawings.

17 denotes a tray of rectangular form made with dimensions suitable for insertion 95 within the interior of the box upon the ledges 15 and 16 whereon it is supported. This tray is filled with candy or confections and then covered over with a sheet of transparent material 18 consisting preferably of the material known in the candy trade as "cellophane." Resting upon the ledges 15 and 16 and having a transparent cover 18, the tray is supported in a position to have its contents visualized through the window 12.

It will be readily understood from the description given that the display extension 10 carrying the tray 17 may be swung into the box to constitute an inset closure or cover 110

for the box, and that it also may be readily swung upwardly into the inclined position illustrated in broken outline in Figs. 1 and 2 for the display of the merchandise housed 5 in the tray. For the support of the display extension 10 and parts supported thereby, in elevated position I provide the sides 13, 14 and reinforced portions 13' 14' therefor with slits or slots 19 and 20, respectively, for 10 straddling engagement upon the top edges of the adjacent sides of the box body. Obviously these slits or slots 19 and 20 are made in the sides at a location remote from the integral hinge or pivot 11.

15 In the use of my improved merchandise holding display box, the display extension 10 may be readily elevated into display position without disturbing in any way the contents of the main box body, and when it 20 is thus raised into elevated position, the contents of the main box body may be removed for sale because of the access that may be had through the space intervening between the depending sides 6 and 7. While the 25 contents of the tray may be seen through the window 12 at all times, the same cannot be molested by prospective customers, owing to the transparent covering 18.

While I have illustrated and described the 30 preferred form of construction for carrying my invention into effect, this is capable of variation and modification without departing from the spirit of the invention. I, therefore, do not wish to be limited to the 35 precise details of construction set forth, but desire to avail myself of such variations and modifications as come within the scope of the appended claims.

Having described my invention, what I 40 claim as new and desire to secure by Letters Patent is:

1. The combination with a box body, of 45 a display top arranged to be supported thereon, said display top having an open end and being provided with depending sheets fitting within, contacting with and reinforced by the sides of the box, and a tray supported on said sheets in relation to said display top and removable through said open 50 end.

2. A display device of the character specified comprising a main receptacle having a wall portion, a display top movable on the wall portion and formed with side portions bent upon themselves to form sides at right angles with the top and also to form ledges in parallelism to the top, and a tray disposed

on said ledges, said sides being enterable within the main receptacle.

3. A display device of the character specified comprising a main receptacle having a wall portion, a display top movable on the wall portion and formed with side portions bent upon themselves to form sides at right angles to the top and also to form ledges in parallelism to the top, said side portions being of a dimension to extend to and engage the bottom of the main receptacle for the support of the top, and a tray disposed on said ledges.

4. The combination with a box body, of a display top arranged to be supported thereon, said display top having an open end and being provided with depending sheets fitting within, contacting with and reinforced by the sides of the box, ledges carried by said sheets in relation to the display member, and a tray disposed on said ledges and removable through said open end.

5. A display device of the character specified comprising a main receptacle having a wall portion, a display top movable on said wall portion and provided with a window, integral side portions on said display top, said side portions being bent upon themselves to constitute reinforced sides and supporting ledges, and means in connection with said reinforced sides and said main receptacle for the support of the display top in display elevation.

6. The combination with a receptacle, of a display top arranged for movement in relation thereto and adapted to be supported thereon, said display top having an open end, side sheets depending from the display top and reinforced by the sides of the receptacle, ledges projecting from said side sheets inwardly of the receptacle, and a tray supported upon said ledges between said side sheets and removable through said open end.

7. A display device of the character specified comprising a box body, a display top movably connected to the box and arranged to be supported thereon, said display top being open at one end, sheets depending from the display member and contacting with the sides of the box and reinforced thereby, and a display tray supported by said sheets in relation to the display member, and removable through said open end.

In testimony whereof I have signed my name to this specification.

FRANK A. PORTMAN.
